CLAIM

The ornamental design for a bicycle safety unit for stunt wheelies, as shown and described.

DESCRIPTION

FIG. 1 is a top and rear perspective view of a bicycle safety unit for stunt wheelies showing my new design;

FIG. 2 is a left side, elevational view thereof, showing my new design, with the right side constituting a mirror-image of the left side;

FIG. 3 is a front elevational view thereof;

FIG. 4 is a rear elevational view thereof; and,

FIG. 5 is a top plan view thereof.

The broken line illustration showing logo indicia positioning is for illustrative purposes only and forms no part of the claimed design.
